UNITED STATES PATENT OFFICE.

EDWARD F. CHANDLER, OF BROOKLYN, NEW YORK.

SECTIONAL CABINET.

Application filed August 23, 1923. Serial No. 653,864.

This invention relates to sectional cases or cabinets used in stores, offices or the like, for filing cards, papers, etc.

It is one of the objects of the invention to 5 provide improved means for assembling the units and for holding them in assembled relation, to form a cabinet.

Another object is to provide a simplified locking means whereby the units can be more 10 economically constructed and yet be rigidly held together when assembled.

Another object is to provide a unit consisting of few parts, in which the use of angle irons or other reinforcing means at the corners may be dispensed with without weakening the units.

Another object is to provide a cabinet unit having a smooth exterior whereby the polishing and finishing of the surface is facilitated 20 and the cost of producing the units is reduced.

Other objects and advantages will appear as the description of the invention proceeds.

Referring now to the drawings which illustrate a preferred embodiment of the invention,

Figure 1 is a perspective view of the cabinet, showing three units assembled, and ready to receive the fourth;

Figure 2 is a sectional view illustrating one means for aligning the units;

Figure 3 is a perspective view of the assembly of a two unit cabinet;

Figure 4 is a perspective view of a two unit locking member;

Figure 5 is a sectional view of the two unit cabinet;

Figure 6 is an end elevation of a corner of a unit;

Figure 7 is a view of the unit blank illustrating a step in the process of forming the corner;

Figure 8 is an end view of a four unit locking member;

Figure 9 is a perspective view showing the recess for the locking member inset from the face of the unit;

Figure 10 is a perspective view showing a modified form of locking member recess;

Figure 11 is a cross-sectional view substantially on the line 11-11 of Figure 10;

Figure 12 is a front view of the shell for a unit;

Figures 12^a and 12^b illustrate various ways of securing the ends of the shell together;

Figure 13 is a view of a modified form of locking member.

In the embodiments illustrated, the cabinet units, which may be of various sizes and of rectangular shape, are designated by the numeral 1. Each unit is provided with an opening 2 in the front thereof, for receiving a drawer or rack to hold the cards, papers or the like for filing. A panel 3 may be provided around the openings 2 to hold the drawers spaced from the walls of the unit. A section of this panel is removed at each corner of the unit as at 4, 4 and the corner walls of the units at each end thereof are displaced inwardly to provide a recess 5 for the body 7 of the locking member 6. The locking members 6 are of various sizes, each comprising a body member 7 and one or more prongs 7^a, 7^b, 7^c, 7^d, etc. A single prong locking member is illustrated in Figure 13, a two prong member in Figure 4, and a four prong member in Figure 8.

To facilitate assembling the units, each unit is provided with displaced dowels or projections 8 upon two of the adjacent sides thereof, for example, upon the top and right side as viewed in Figure 1, and with corresponding sockets or depressions 9 upon the opposite sides, i. e., the bottom and left side in Figure 1, to receive the projections 8 and hold the units in position to receive the locking members 6. The projections 8 and depressions 9 may each be formed by displacing the walls of the units a slight amount, as illustrated in Figure 2.

To assemble the cabinet, as illustrated in Figure 1, the fourth unit is positioned upon the single unit to complete the rectangle, four pronged locking members 6 are inserted at each end of the cabinet at 10, two pronged locking members are inserted in the recesses at 11, and single pronged members are inserted at the outer corners 12. When inserted, the body 7 of the locking members substantially fills the recesses 5 and forms a cabinet with a smooth exterior, while the prongs 7^a, 7^b, 7^c, etc., project into the separate units to hold or lock them in assembled position.

It will be observed that by means of this construction, each unit, and each combination of units, when complete with the locking members, will have perfectly smooth sides. As stated above, this constitutes an advantage from a manufacturing standpoint, inasmuch as the cost of finishing flat surfaces is considerably less than that entailed by the finishing of irregular surfaces. However, aside from considerations of cost, this feature

is very important per se, because the appearance of the cabinets is much improved, it being the same as that of ordinary non-sectional cabinets, and the weight is uniformly distributed over a large surface. Furthermore, there being no projecting parts and corners where the dust can collect, it is easier to maintain the cabinets clean. Moreover, it is possible to set cabinets formed by means 10 of these units, side by side with cabinets of ordinary construction, without danger of scratching or marring their surfaces.

While a cabinet consisting of four substantially uniform units has been illustrated 15 and described, it is to be understood that any number of units of various sizes may be assembled together to form a cabinet and that suitable bases and cap pieces may be provided for the top and bottom of the cabinet 20 to form an attractive piece of furniture.

A special feature of my invention is the simplified method of constructing the units of my cabinet, which are preferably formed from one piece of sheet material, shaped to 25 form a rectangle 13, as illustrated in Figure 12, with the ends of the sheet joined by a strip 14 covering the seam. In lieu of the strip 14, the ends of the sheet may be connected by a lap joint 14^a which is spot welded 30 or by a lock seam 14^b which may be used to hold the ends together without welding. The recesses 5, for receiving the locking members 6, are formed by displacing a part of the corner wall of the unit inwardly in a manner to be described. For forming the panels 3 and the recesses 5 at the corners of the cabinet, the sheet is cut to the shape shown in Figure 7. The wings 3^a to form the panel 3 are cut away at the corners 3^b so as to form 40 a smooth joint when the wings 3^a are folded down to form the panel. The notch 5^a is formed to leave an opening into recess 5 for the insertion of the locking members. The sheet is then slotted at 5^b to permit the walls 45 of the recess 5 to be shaped therefrom. In the manufacturing process, the walls 1^b are folded toward each other along the line 1^c to form a 90-degree angle, and the portion 5^c is folded inwardly along the lines 5^d to form 50 90-degree angles with the walls 1^b and complete the rectangular recess 5. The wings 3^a are then folded inward along the lines 3^b to form the panel 3. The completed corner 55 as formed by these operations, is illustrated in Figure 6.

Figure 9 illustrates a modification of the invention in which the recess 5^e for the locking member is inset from the face of the unit whereby the cabinet, when assembled, will 60 present smooth end surfaces. The recesses 5^e are longer than the total length of the locking members 6, so that in assembling the units having the recesses inset from the ends, the proper locking member is dropped into 65 the recess before the covering units are as-

sembled, and when the completed cabinet is assembled the locking members may be pushed into locking engagement with the walls by inserting the arm through the openings 2 and using the fingers to push the prongs 70 of the locking members in recesses 5^e forward into engagement with the inner walls of each unit adjacent the recesses 5^e.

Figures 10 and 11 illustrate still further modifications in which the recess for the locking member is inset from the face of the unit and is formed by cutting away the wall of the unit at 5^f and attaching an angle member 5^g to the walls 1^c at the edge of the opening 5^f to form a pocket in which the prongs 7^a, 7^b, etc., fit, while the body 7 of the locking member projects through openings 5^f into the units.

It is to be noted here that the integral panels 3 and the recesses 5 form reinforcements for the corners and end of the units to hold them rigid without the necessity for attaching separate sections of angle irons or the like to the walls.

In accordance with the patent statutes, I have described a preferred embodiment of my invention, but it is to be understood that various modifications may be made therein without departing from the spirit of the invention or the scope of the accompanying 95 claims.

What I claim is:

1. In combination, a plurality of sectional cabinet units, each comprising a rectangular shell having flush faces, said shells having 100 complementary key-receiving openings in adjoining edges thereof letting into the interiors of the shells, and a freely slideable pronged key inserted in said openings with its prongs 105 entering the respective cabinet sections and exposed interiorly thereof and embracing adjacent walls of the shells to lock them together.

2. In a sectional cabinet unit, a rectangular shell having flush faces and having a key-receiving opening provided at an edge thereof and letting into the interior of the shell, so that a key or filler inserted in said opening may be exposed interiorly of the shell, and means extending inwardly from an inner face 110 of the shell for supporting the key or filler inserted through said opening.

3. In a sectional cabinet unit, a rectangular shell having flush faces, and provided at one of its edges with a key-receiving opening letting into the interior of the shell, and a key inserted to lie partially within and partially without the shell, the opening and the key being so shaped that the exposed portion of the key may be flush with the exterior of the shell.

In testimony whereof I have affixed my signature to this specification.

EDWARD F. CHANDLER.
